UNITED STATES PATENT OFFICE.

NICHOLAS SIMON, OF NEENAH, WISCONSIN.

DESIGN FOR A CHEESE-MOLD.

SPECIFICATION forming part of Design No. 34,726, dated July 2, 1901.

Application filed May 27, 1901. Serial No. 62,170. Term of patent 14 years.

To all whom it may concern:

Be it known that I, NICHOLAS SIMON, a citizen of the United States, residing at Neenah, in the county of Winnebago and State of Wisconsin, have invented and produced a new and original Design for a Cheese-Mold, of which the following is a specification, reference being had to the accompanying drawings, forming part thereof.

Figure 1 is a plan of the mold, and Fig. 2 is a vertical section taken upon the line *a a* of Fig. 1.

As shown in the drawings, the leading features of my design consist of a square mold having sides 1, a bottom 2, having perforations 3, oval-shaped ribs 4 and 5, projecting above the surface of the bottom and inward from the sides of the mold, respectively, a re-

cess 6 in the upper part of the mold for receiving a sheet-metal cheese-cloth holder, a band 7 around the outside of the mold, and handles 8 upon opposite sides of the mold, all of said parts being formed integral of a suitable cast metal.

Having described my said invention, what I claim, and desire to secure by Letters Patent, is—

The design for a cheese-mold as herein shown and described.

In testimony whereof I have signed my name in the presence of two subscribing witnesses.

NICHOLAS SIMON.

Witnesses:

S. D. BAIRD,
L. A. ROSENTHAL.
